UNITED STATES PATENT OFFICE.

OTTO J. KUENHOLD, OF CLEVELAND, OHIO, ASSIGNOR TO THE SCIENTIFIC HEATER COMPANY, OF CLEVELAND, OHIO, A CORPORATION OF OHIO.

GARAGE-HEATER.

1,329,716.

Specification of Letters Patent.

Patented Feb. 3, 1920.

Application filed May 6, 1918. Serial No. 232,772.

To all whom it may concern:

Be it known that I, OTTO J. KUENHOLD, citizen of the United States, residing at Cleveland, in the county of Cuyahoga and State of Ohio, have invented certain new and useful Improvements in Garage-Heaters, of which the following is a specification.

This invention relates to heating devices, and more particularly to heating devices including a burner in a closed or substantially closed chamber, such as the heating chamber for the oven of an ordinary gas range, or the burner chamber of a garage heater or the like.

The invention has particular relation to the means or mechanism for igniting the burner, its object being to provide igniting means which is simple to operate, which is not liable to get out of order in service, and which can be made and sold at low cost.

Further objects of the invention are in part obvious and in part will appear more in detail hereinafter.

The invention comprises the construction and arrangement of parts hereinafter described and claimed.

In the drawings, which represent one embodiment of the invention, Figure 1 is a broken out sectional elevation through a portion of one form of garage heater embodying the invention; Fig. 2 is a front elevation, on a larger scale, of the igniting device; Fig. 3 is a sectional elevation on the line 3—3, Fig. 2, looking in the direction of the arrows; Fig. 4 is a detail section of an igniting pencil; and Fig. 5 is a detail section corresponding to Fig. 3, and illustrating a modification.

The invention is capable of application to any form of heating device where the burner is within a chamber and therefore difficult to reach for igniting purposes, or where for any reason it is desirable to ignite a burner within a chamber from the outside thereof.

For purposes of illustration and not in any sense as limiting the invention it has been shown as applied to a garage heater of the same general form illustrated in my prior application for heaters for garages and other purposes, filed December 13, 1915, Serial No. 66,652, to which reference may be had for a more complete description of the heater.

The heater as a whole may be of any suitable or desired construction, the present

invention being concerned more particularly with the igniting device. Nevertheless, the heater is preferably constructed along safe lines to meet requirements of the fire underwriters, who desire no access of the flame to inflammable gases in the open atmosphere of the garage, such as is possible, for example, in a heater having an openable door through which a lighted match or taper is inserted for lighting the burner. The present heater is therefore constructed to avoid all possibility of contact of the flame with the open atmosphere.

As illustrated the heater comprises a suitable outer casing or jacket 1 supported upon the floor and having both its bottom and top open to the atmosphere. Within said outer jacket is a hollow drum 2 which is of air tight construction, except for an outlet at the rear through which the products of combustion are discharged and a screened inlet 3 through which air is admitted for combustion to the inner drum chamber. Within the drum is a gas burner 4 connected to a supply pipe 5 having the usual regulating valve 6. The screen 3 may be of single or double form, its function being to permit air for combustion to flow to the burner and at the same time to prevent passage of the flame from the inner drum chamber to the outer open atmosphere.

The front wall of the heater is provided with a plate 7 through which the supply pipe 5 extends, and which plate also serves to support a pilot light and the igniting devices to be referred to. This plate has a window 8 through which the flame can be inspected and is also provided with an opening 9 closed by a metal frame 10 securely bolted or otherwise secured to said plate. In said frame is an opening 11 through which extends a pilot burner 12 having a valve 13 and connected by a pipe 14 to the supply pipe 5. The pilot burner 12 is located adjacent to the burner 4, so that the pilot flame, when burning, will ignite the jets of the main burner.

The igniting device for the pilot burner is so arranged as to be capable of actuation from the outside of the heating drum and nevertheless prevents passage of flame to the outside of said drum. Said igniting device preferably includes a piece of pyrophoric material, which is a substance of well known characteristics, together with a

roughened member for rubbing the same and producing the igniting sparks. As illustrated the rubbing member is a wheel or disk 15 having a roughened surface, such as the milled periphery 16, said wheel being carried by a shaft 17 extending through an opening in the frame 10 to the outside thereof, its projecting end portion being roughened, as at 18, to enable it to be readily turned with the fingers to produce the rubbing action. The axis of shaft 17 is inclined downwardly from the front toward the interior of the drum, and the lower portion of the milled surface 16 lies at one side of and horizontally opposite the inner end of the pilot burner 12.

Beneath the rubbing member 15 the frame 10 is provided with a boss 19 having a hollow passage 20 whose axis is perpendicular to the shaft 17 and lies directly opposite the rubbing member 15. Said boss 19 is also provided with suitable means for normally closing the passage 20. For this purpose, it is provided with a second opening or channel 21 intersecting the passage 20, said channel 21 having a seat 22 at its lower end. In the channel 21 is a closing member for the channel 20, such, for example, as a fairly large ball 23 normally held by gravity or a light spring to the seat 22, and which, when in position on said seat, closes the passage 20 and prevents the passage of any flame from the inner drum chamber to the outside of the heater. The ball 23 may be inserted through the upper end of the passage 21, which is subsequently closed by a suitable plug 24.

As illustrated in Fig. 4 the passage closing member may be a plunger 23^a having a rounded lower end to fit the seat 22 and held to its seat either by gravity or a light spring 25 beneath the plug 24. The same kind of spring may be used in connection with the ball 23, if desired.

The purpose of the passage 20 is to enable a suitable device to be inserted therethrough into coöperating relation with the member 15, so that rotation of said member in contact with said device will produce incandescence to ignite the pilot burner. The device shown for this purpose is a tubular pencil 27 shown in Fig. 4 and to one end of which is secured a small piece 28 of pyrophoric material. The pencil 27 is slightly longer than the channel 20 so that it can be pushed therethrough to bring the pyrophoric material into contact with the member 15, rotation of which against said material produces incandescence and ignites the pilot burner. The opposite end of the pencil is hollow, the cavity therein serving to hold an ordinary match 29. Said tube 27 may have a suitable stop for the inner end of the match, such as the bent tongue 30. In case the pyrophoric material is worn out or broken so

that it will not operate, an ordinary match can be inserted into the pencil, as shown in Fig. 4, and pushed into contact with the member 15 so that rotation of said member will again produce incandescence and a flash 70 and therefore light the pilot burner.

Insertion of the pencil 27 pushes the passage closing member 23 or 23^a into its channel 21, and upon removal of said pencil the closing member returns to its normal position and closes the passage.

The tube 27 and passage 20 are of such size and length that when a match is used the retraction of said match through the small channel will put out the match flame. 80 The return of the ball 23 to its seat also assists in extinguishing the match flame. Consequently there is no liability of communicating flame to the outside air.

The construction described is simple and 85 offers perfect protection against the possibility of igniting inflammable gases in the garage. At the same time the pyrophoric material is normally held away from the rubbing member 15 and can therefore be 90 wiped dry so that it will always operate properly.

What I claim is:

1. In combination, a casing provided with 95 a burner chamber, a burner within said chamber, one wall of said chamber being provided with an opening through which an igniting member may be inserted, means normally closing said opening and operable to open the same only by insertion of said member, and a rubbing member within said chamber operable from the outside thereof.

2. In combination, a casing provided with a burner chamber, a burner within said chamber, one wall of said chamber being 105 provided with a passage through which an igniting member may be inserted, and a yielding valve normally obstructing and closing said passage between its ends and operable to open the same only by insertion 110 of said member.

3. In combination, a casing provided with a burner chamber, a burner within said chamber, one wall of said chamber being 115 provided with a passage, an igniting member for insertion through said opening, said member being arranged to support a device capable when rubbed of producing incandescence, a rubbing member within said chamber beyond the end of said passage and operable from the outside of said chamber, and means normally closing said passage and operable to open the same only by insertion of said member.

4. In combination, a casing provided with 125 a burner chamber, a burner within said chamber, one wall of said chamber being provided with a passage, an igniting pencil for insertion through said passage and adapted to substantially fill the same, and a 130

coöperating rubbing member within said chamber beyond the end of said passage and operable from the outside of said chamber, said pencil at one end carrying a piece of pyrophoric material.

5. In combination, a casing provided with a burner chamber, a burner within said chamber, one wall of said chamber being provided with a passage, an igniting pencil for insertion through said opening and adapted to substantially fill the same, and a coöperating rubbing member within said chamber and operable from the outside thereof, said pencil at one end carrying a piece of pyrophoric material and at the other end being arranged to support a match.

6. In combination, a casing provided with a burner chamber, a burner within said chamber, one wall of said chamber being provided with a passage, an igniting pencil for insertion through said opening and adapted to substantially fill the same, a coöperating rubbing member within said chamber and operable from the outside thereof, and yielding means normally closing said passage and operable to open the same only by insertion of said pencil.

7. In combination, a casing provided with a burner chamber, a burner within said chamber, one wall of said chamber being provided with a passage, an igniting pencil for insertion through said opening and adapted to substantially fill the same, a

coöperating rubbing member within said chamber and operable from the outside thereof, said pencil at one end carrying a piece of pyrophoric material, and yielding means normally closing said passage and operable to open the same only by insertion of said pencil.

8. In combination, a casing provided with a burner chamber, a burner within said chamber, one wall of said chamber being provided with a passage, an igniting pencil for insertion through said opening and adapted to substantially fill the same, a coöperating rubbing member within said chamber and operable from the outside thereof, said pencil at one end carrying a piece of pyrophoric material and at the other end being arranged to support a match, and yielding means normally closing said passage and operable to open the same only by insertion of said pencil.

9. In combination, a casing provided with a burner chamber, a burner within said chamber, one wall of said chamber being provided with a cylindrical passage, an igniting pencil insertible through said passage and substantially filling the same, a coöperating rubbing member within said chamber, said wall having a passage intersecting said first passage, and a yielding device in said second passage adapted to normally close said first passage.

In testimony whereof I affix my signature.
OTTO J. KUENHOLD.
